United States Patent Office

Des. 211,556
Patented July 2, 1968

211,556

SLIPPER OR SIMILAR ARTICLE

Martin Sherman, 31-09 Bessemund Ave.,
Far Rockaway, N.Y. 11691

Filed Mar. 20, 1967, Ser. No. 6,302

Term of patent 7 years

(Cl. D2—279)

FIG. 1 is a front and side perspective view of a slipper or similar article embodying my new design,

FIG. 2 is a top plan view thereof,

FIG. 3 is a side elevational view thereof,

FIG. 4 is a front elevational view thereof, and

FIG. 5 is a rear elevational view thereof.

I claim:

The ornamental design for a slipper or similar article, substantially as shown.
